SUPPORT CAP

Robert Henry Alexander and John Karl Specht, Warren, Pa., assignors, by mesne assignments, to Sylvania Electric Products Inc., Wilmington, Del., a corporation of Delaware

Filed Aug. 31, 1955, Ser. No. 531,759
2 Claims. (Cl. 24—73)

This invention relates to a support cap for fragile articles and more particularly to a cap for supporting Christmas tree ornaments.

Christmas tree ornaments of the type formed to give the appearance of colored glass spheres or bulbs are usually attached to the branch of the tree by a metallic cap assembly and a wire or string. The metallic cap assembly comprises a cap having a wall which surrounds and engages the exterior surface of the bulb neck and a base formed with an aperture through which a resilient wire spring is threaded. The spring is shaped so that it may be depressed during entry into the bulb neck opening, and will flex outwardly and contact the inner surface of the bulb after insertion. This type of cap assembly is thereby affixed to the bulb by means of the internally disposed spring contact wires and the externally disposed cap walls which cooperate with the bulb neck. That portion of the spring wire arranged outside the bulb is usually formed to provide a loop through which a string or wire hook is threaded to effectively hang the ornament from a tree limb.

Ornament support device assemblies of the type described above have two components, the cap and spring, each of which must be fabricated separately and subsequently assembled. This assembly must then be mounted upon the ornament manually due to its awkward configuration, the necessity of depressing the spring for insertion, and the fragile nature of the ornament. Even with manual operation, numerous ornaments are broken when the spring ends catch on the edge of the ornament neck during assembly.

It is therefore an object of the invention to provide a support for a fragile article which is simple in design and economical to manufacture.

A further object is the provision of supporting means for a fragile article which is suitable for automatic fabrication and assembly.

A still further object is to provide a support for a fragile article which minimizes breakage during assembly, later handling and ultimate use.

The afore-mentioned objects are achieved in one aspect of the invention by the provision of a cap for supporting an ornament formed from a flexible material to provide a base with a wall which engages the exterior marginal portions of the ornament opening and integral resilient appendages which grasp the internal surface of the ornament.

Other objects will be apparent after reading the following description taken in conjunction with the accompanying drawings in which:

FIG. 1 is a plan view of one embodiment of the invention;

FIG. 2 is a section taken along line 2—2 of FIG. 1;
FIG. 3 is another embodiment of the invention;

FIGS. 4 and 5 are sectional views taken along lines 4—4 and 5—5 respectively of FIG. 3; and

FIG. 6 is a partial view of the embodiment shown in FIG. 3 in a cooperating relationship with an ornament.

Referring to FIGS. 1 and 2, the cap 11 as shown as having a circular base 13, which is formed to cooperate with the circular neck of an ornament similar to the one shown in FIG. 6. However, bases with other shapes may

2

be employed if another type of ornament configuration is used. Cap 11 may be made of a plastic material such as polyethylene or of another material having the characteristics of being flexible and resilient. Integral with base 13 is a raised portion 15, appendages 17, and a wall 19 shown in FIG. 2 as completely surrounding appendages 17 and having a height greater than the appendages.

The cap mounting member or raised portion 15 has an aperture 21 preferably formed as a slot to provide the channel through which a tree limb engaging string or wire may be threaded. Referring to FIG. 2, each appendage 17 is shown as having a leg section 23 and a foot 25. The appendages cooperate with an ornament bulb neck of the type illustrated in FIG. 6 to effectively retain the neck 19 between the appendages and wall 19 when these parts are in an operable relationship with one another. Although four appendages 17 are shown in the embodiment of the invention illustrated by FIGS. 1 and 2, the number employed may be varied to give the amount of grasping action desired. Since the material of the cap is resilient, appendages 17 are forced inwardly by the walls of the ornament neck as the neck is slid intermediate appendages 17 and wall 19, and over the tapered ends of feet 25. When the edge of the ornament neck reaches an abutting position with the lower surface of base 13, resilient appendages 17 are pressed against the inner surface of the ornament neck so that the ends of feet 25 frictionally engage the wall of the ornament neck and thereby retain it between appendages 17 and wall 19.

This construction of resilient cap 11 allows it to be automatically assembled on the ornament by a suction arm or similar device without causing cracked or chipped ornament necks.

Another embodiment of the ornament cap constituting one aspect of the invention is shown in FIGS. 3 to 6 inclusive. Integral with circular base 29 is a cap mounting member or raised portion 31, appendages 33, wall 35, and protrusions 37. Raised portion 31 has a slot 39 formed therein to provide means through which a tree limb engaging string or wire 41 may be threaded. Resilient base 29 has a curved surface formed to provide a depression at its central section, thereby causing appendages 33 to extend from base 29 at an angle with wall 35. The appendages have tapered or rounded ends so that contact with the glass ornament will not crack the ornament neck during insertion. Although three appendages are shown, the number may be varied to give the amount of frictional engagement desired. Cap wall 35 surrounds appendages 33 and has a shape corresponding to the shape of the ornament neck. However, if an ornament is employed which does not have a well-defined neck portion, wall 35 may be accordingly altered or eliminated, provided the base 29 is made wide enough to cover the ornament opening and provide a proper seat for the cap. Three semi-circular protrusions 37 may be arranged on the internal surface of walls 35 intermediate the positions of appendages 33 to provide additional engagement with the ornament neck. The protrusions may also be in the form of a partial rim or a complete rim circumscribing the internal surface of wall 35.

The embodiment shown in FIGS. 3 to 6 may also be applied to ornament 43 by an automatic machine. A vacuum chuck or similar device may be placed against the top surface of base 29 causing it to be forced outwardly to assume the form of a substantially flat plane. This movement of the base also causes integral appendages 33 to move to a position substantially parallel to wall 35. The vacuum chuck may then be moved to thread the cap over neck 45 of ornament 43 so that the marginal portions of the ornament opening lies intermediate appendages 33 and protrusions 37. Release of

the vacuum then allows base 29 to return to its normally curved form, which in turn disposes appendages 33 at an angle with ornament neck wall 45. The ornament wall is thereby trapped between appendages 33 and protrusions 37. Frictional engagement of the appendages and the protrusions with the ornament neck provides adequate support for the ornament when it is hung from the limb of a tree. Protrusions 37 may be eliminated if desired, and sufficient ornament support can be obtained by frictional engagement with appendages 33 and wall 35.

Ornament caps or other supports for light articles made in accordance with the invention may be mass produced as a single piece and are adaptable for automatic production assembly methods while at the same time lending to the reduction of rejects due to broken ornaments.

While there has been shown and described what at present is considered to be several preferred embodiments of the invention, it will be apparent to persons skilled in the art that other modifications may be made therein without departing from the scope and spirit of the invention as defined by the appended claims.

What is claimed is:

1. A plastic cap adapted for slidable attachment to and support of a fragile article having a substantially straight open neck portion of a given thickness comprising a curvilinear resilient base, a substantially uniformly thick wall surrounding said base, a cap mounting member integral with said base, and a plurality of spaced apart integral resilient appendages depending from said base internally of and in the same direction and at an angle to the wall, the ends of said appendages being normally spaced from the wall a distance less than said given neck portion thick-

ness whereby said wall and said appendages are frictionally engaged with opposite sides of said neck portion and spatially yield to said given thickness to provide support for said article upon slidable attachment of said cap thereto.

2. A plastic cap adapted for slidable attachment to and support of a fragile article having a substantially straight open neck portion of a given thickness comprising a base, a substantially uniformly thick wall surrounding said base formed with protrusions, a cap mounting member integral with said base, and a plurality of spaced apart integral resilient appendages depending from said base, internally of and in the same direction and at an angle to the wall, the ends of said appendages being normally spaced from the wall a distance less than said given neck portion thickness whereby said protrusions and said appendages are frictionally engaged with opposite sides of said neck portion and spatially yield to said given thickness to provide support for said article upon slidable attachment of said cap thereto.
